UNITED STATES PATENT OFFICE.

MOSES MOSLER, OF CINCINNATI, OHIO, ASSIGNOR TO THE MOSLER SAFE COMPANY, OF NEW YORK, N. Y.

SAFE.

SPECIFICATION forming part of Letters Patent No. 575,806, dated January 12, 1897.

Application filed August 21, 1896. Serial No. 603,438. (No model.)

To all whom it may concern:

Be it known that I, MOSES MOSLER, of Cincinnati, Hamilton county, Ohio, have invented certain new and useful Improvements 5 in Burglar-Proof Safes, of which the following is a specification.

There is in common use a class of burglar-proof safes consisting of a shell of drill-proof material provided with an inwardly-opening 10 door, the door being arranged to move inwardly to free it from its jambs and then turn upon a vertical axis to carry it to the rear of the chamber within the shell, the treasure-receptacle turning with the door and coming to 15 the opening in the shell as the door takes its position of retreat.

My invention pertains to improvements in this general class of safes, and my improvements will be readily understood from the following description, taken in connection with the accompanying drawings, in which—

Figure 1 is a vertical axial section, plane of line *a* of Fig. 2, of a safe exemplifying my invention, the parts being in the position 25 corresponding with the closed and locked position of the safe; Fig. 2, a horizontal section of the same in the plane of line *b* of Fig. 1, the interior parts appearing in plan, the door being in condition of retreat from its jamb 30 to permit the inner structure to be turned; Fig. 3, a view similar to Fig. 2, but with the inner structure turned through an angle of ninety degrees; Fig. 4, a similar view, but with the inner structure turned through an 35 angle of one hundred and eighty degrees to bring the treasure-compartment to the front; Fig. 5, a vertical section, plane of line *c* of Fig. 1, of a portion of the shell and showing a portion of the door in rear elevation and in 40 locked condition; Fig. 6, a front elevation of the treasure-chest; Fig. 7, a plan of door and treasure-chest, a portion of the latter appearing in horizontal section in the plane of line *b* of Figs. 6 and 8; and Fig. 8, a side elevation 45 of the treasure-chest. Figs. 6, 7, and 8 are on a smaller scale than the remainder of the figures.

In the drawings, referring for the present to Fig. 1, 1 indicates a shell of drill-proof 50 material and provided at its front with a circular opening or door-jamb, which opening

is of tapering character, being smaller at the front; 2, the door, its periphery fitting the door-jamb; 3, an air-tight seating of the periphery of the door within its jamb, this seating being tapering, with its smaller portion outwardly; 4, screw-threads on the door and door-jamb to the rear of the seating 3, the threads being preferably in ratchet form and the screw formed by them forming a quick 60 taper, the larger end of the screw being inward; 5, a screw projecting concentrically from the inner face of the door and having a pitch corresponding with that of thread 4; 6, a yoke-disk supported within the shell parallel with the rear face of the door when the door is in closed condition, as in Fig. 1; 7, a nut at the center of this yoke-disk and engaged by screw 5, so that as the door is unscrewed inwardly on its threads 4 it becomes 70 supported by screw 5 in the yoke-disk; 8, a pair of vertical pintles carried by the yoke-disk and engaging the shell and forming the axis of rotation of the inner structure of the safe; 9, a treasure-chest formed by a casing 75 carried by the yoke-disk and extending rearwardly therefrom into the rear of the shell-chamber, and 10 a doorway in the rear wall of treasure-chest 9.

Viewing Fig. 1, the only figure of the drawings thus far considered, it will be observed that door 2 is seated in its jamb, tightly fitting at seating 3, and firmly held by threads 4. To remove the door outwardly would require force sufficient to burst the shell. To remove 85 the door directly inwardly or to turn it orbitally would require force sufficient to strip threads 4 and 5 and break the yoke. It follows that the door can be unseated only by unscrewing it inwardly from its jamb. 90

By unscrewing the door inwardly it retreats toward yoke-plate 6 and disengages threads 4 and seating 3, leaving the parts in the position indicated in Fig. 2. In this condition the inner structure, formed by the door, the yoke-disk, and the treasure-chest, is at liberty to be rotated on pintles 8. It may be first turned to an angle of ninety degrees, as indicated in Fig. 3, and then through another ninety degrees to the position indicated in Fig. 4, thus 100 bringing the opening 10 of the treasure-chest to the front of the safe. This is the open con-

dition of the safe. To close the safe the inner structure is turned back to the position indicated in Fig. 3, and then to the position indicated in Fig. 2, and the door is then to be 5 screwed outwardly till home and in the position indicated in Fig. 1.

When the safe is closed, its locking is effected by automatic time-lock mechanism disposed entirely within the safe and having no 10 communication with the exterior of the safe. Locking mechanism of an exemplifying character will now be described.

Referring further to the drawings, 11, Fig. 5, indicates a notch cut in the interior thread 15 of the shell; 12, a recess in the inner face of the door in a position corresponding with the locality of notch 11, that is to say, when the door is screwed home, recess 12 will come at notch 11; 13, a pawl pivoted to the door 20 in recess 12, its point engaging in notch 11 against the end of the shell-thread formed by the cutting of that notch, the direction of action of the pawl being such that the pawl engaging the end of the shell-thread at the 25 notch prevents the unscrewing of the door; 14, a flexible lever projecting from the pawl, this lever being a spring with its free end extending rearwardly and lying against the front face of the yoke-plate, as indicated in 30 Fig. 7; 15, a pin projecting rearwardly from the end of lever 14; 16, a concentric groove in the rear face of yoke-plate 6, this groove being engaged by pin 15, the radial position of the groove being such as corresponds with the 35 position of pin 15 when pawl 13 is inward out of engagement with the shell-thread; 17, the time-lock, of any ordinary construction, disposed in one side of the treasure-chest at a suitable opening in the side wall thereof, and 40 18 a block sliding radially in a groove in the rear face of yoke-disk 6 and having in its front face a segment of groove 16, the time-lock serving to operate this block and move it outwardly so that the groove in the block 45 coincides with groove 16 in the yoke-disk, or to move it inwardly into the position indicated in Fig. 6, in which position the groove in the block corresponds with the position of pin 15 when pawl 13 is engaging the shell-thread.

Block 18 is in such angular position on yoke-disk 6 as corresponds with the position of pin 15 when the door is closed and pawl 13 in engagement with the pawl-thread. In 55 this condition the time-lock is inert and the safe is locked by the pawl. At the proper time, as controlled by the setting of the time-lock, block 18 moves outwardly, carrying pin 15 to the radial position of groove 16. 60 This motion of the block unlatches the pawl from its notch and permits the door to be unscrewed, in the course of which unscrewing motion pin 15 travels around in groove 16, the flexing of lever 14 compensating for the 65 approach of the door toward the yoke-disk. When the safe is to be closed, the door is screwed home and the time-lock moves the

pawl to latching position, where it remains till the predetermined time of opening arrives.

When the inner structure is in the half-way position indicated by Fig. 3, then time-lock 17 becomes presented at the front of the safe, giving convenient access for setting, &c. The improved safe may have any or all of the usual adjuncts of safes of this character. 75 Thus, for instance, the structure may be provided with a supporting-base. The exterior of the door may be provided with "day-locking" attachments, as is common in screw-door safes dependent on isolated interior locking devices for their burglar-proof locking security. The treasure-chest may be divided into interior compartments and have a door at its opening 10. For small safes the screw-door may be turned by a suitable implement 85 applied at the non-circular socket indicated in Fig. 1. For large safes gearing may be applied to the door as is usual in large screw-door safes.

The shell of the safe may be formed of the 90 material and in the manner usual in safes of the above generally described character.

I claim as my invention—

1. In a safe, the combination, substantially as set forth, of a shell having a threaded circular door-opening, a yoke mounted on pintles within said shell, and a door carried by said yoke and adapted for movement to and from the yoke and having a threaded periphery adapted to engage the threads of the 100 door-jamb by screwing outwardly into the same.

2. In a safe, the combination, substantially as set forth, of a shell having a circular door-jamb provided with threads and having a tapering seat enlarging inwardly, a yoke mounted on pintles within the shell, and a door carried by said yoke and having a threaded periphery provided with threads and a seating adapted to engage said jamb. 110

3. In a safe, the combination, substantially as set forth, of a shell having a circular door-jamb provided with a tapering thread enlarging inwardly, a yoke mounted on pintles within the shell, and a door carried by said 115 yoke and having its periphery provided with a tapering screw to fit the threads of said jamb.

4. In a safe, the combination, substantially as set forth, of a shell having a circular 120 threaded door-jamb, a door having its periphery provided with threads to engage said door-jamb by screwing outwardly thereinto, a yoke supported on pintles within the shell, and a screw projecting centrally from the 125 door into engagement with said yoke and having a thread corresponding in pitch with the thread on the jamb.

5. In a safe, the combination, substantially as set forth, of a shell having a circular door-jamb of tapering character enlarging inwardly, a yoke supported on pintles within the shell, a rotary door connected with said yoke and having its periphery formed to fit 130

said jamb, and a screw upon said door adapted to move the door inwardly from its jamb as the door is turned upon the axis of such screw.

6. In a safe, the combination, substantially as set forth, of a shell having a circular door-jamb, a yoke mounted upon pintles within said shell, a rotary door connected with said yoke and closing said jamb by moving outwardly thereinto, a screw upon the door for moving the door inwardly out of said jamb as the door is rotated upon the axis of said screw, a latch carried by the door within the shell and adapted to engage an obstruction in the shell and prevent the rotation of the door upon the axis of said screw, a time-lock car-

ried by said yoke, and connections between said time-lock and latch.

7. In a safe, the combination, substantially as set forth, of a shell having a circular door-jamb, a yoke mounted on pintles within the shell and carrying a treasure-chest, a rotary door carried by the yoke and adapted to close said jamb by moving outwardly thereinto, and a screw on said door for moving the door into engagement with said jamb as the door is turned upon the axis of said screw.

MOSES MOSLER.
